UNITED STATES PATENT OFFICE.

GEORGE RUPPEL, OF NEW ORLEANS, LOUISIANA.

GASOLENE-LAMP.

SPECIFICATION forming part of Letters Patent No. 670,484, dated March 26, 1901.

Application filed May 3, 1900. Serial No. 15,409. (No model.)

To all whom it may concern:

Be it known that I, GEORGE RUPPEL, a citizen of the United States of America, residing at New Orleans, in the parish of Orleans and State of Louisiana, have invented certain new and useful Improvements in Gasolene-Lamps; and I do hereby declare the following to be a full, clear, and exact description thereof, reference being had to the accompanying drawings, which form a part of this specification.

This invention relates to an improvement in gasolene or vapor lamps; and the object is to provide a lamp of simple construction and having a novel form of vaporizing-tube that may be readily removed for cleaning or the like, together with certain details of construction and combination of parts, as will be fully described hereinafter.

Reference is to be had to the accompanying drawings, forming a part of this specification, in which similar characters of reference indicate corresponding parts in theseveral figures.

Figure 1 is a side elevation of my improved lamp, a portion of which is shown in section. Fig. 2 is an enlarged sectional plan view of the same, the said section taken on the line X X of Fig. 1. Fig. 3 is a side elevation of a modified form of my improved lamp, partly shown in section, and in which the vaporizing-tube is arranged in a vertical position instead of horizontal, as shown at Fig. 1 of the drawings. Fig. 4 is an end elevation of a portion of the same. Fig. 5 is an enlarged detailed sectional elevation of the nipple arranged in the discharge end of the vaporizing-tube.

Referring to the drawings, Figs. 1, 2, and 5, 1 designates a supply-pipe which communicates with a pipe 2, leading from a tank for containing the gasolene or other hydrocarbon oil, and whereby the oil may be supplied to the lamp under pressure. A ring 3, attached to the pipe 1, affords a means for suspending the lamp from a hook or the like.

Attached to the lower portion of the pipe 1 is a coupling 4, and engaging with this coupling is a valve-casing 5, in which a cut-off valve 6 is arranged. Communication is provided between the pipe 1 and the valve-casing by means of a tube 7, and removably connected to the valve-casing is a vaporizing-tube 8. This vaporizing-tube is provided

with a flaring or bell-shaped end portion 9 for engaging with the correspondingly-shaped end of the valve-casing 5. The tube is held 55 removably in place by means of a coupling-thimble 10, having a screw-thread engagement with the valve-casing and engaging with the bell-shaped portion 9 of the tube 8. The other end of the vaporizing-tube 8 has a 60 nipple 8^a and is inserted in a socket 11, arranged at one end of a vaporizing-pan 12, connected to a mixing tube or chamber 13, extended from the coupling. This tube 13 is provided with a bell-mouth entrance, and 65 extended through the same and through the coupling 4 is a distributor, consisting of a stem 14, terminating in a conical head 15, which is designed to be adjusted toward or away from the outlet end of the tube and for 70 the purpose of thoroughly separating the vapor discharged from said tube 8 and mixing it with air before passing into the tube 13.

Having screw-thread engagement with the coupling 4 and communicating with the tube 75 13 is the mixing-tube 16, which communicates with the burner 17, which supports a holder 18 for a lamp-globe 19. By providing a screw-thread engagement between the pipe 16 and the coupling 4 the mixing-tube 16, carrying 80 the burner and the globe, may be swung outward relatively to the vaporizing-tube when it is desired to remove the globe 19 or to clean the burner. As the vaporizing-tube is directly over the burner, the heat will cause the oil 85 to become vaporized, so as to mix with the atmospheric air.

It is obvious that any number of lamps may be connected to the one supply-tank and each one may be cut out upon closing the valve 6. 90

In starting the lamp a small amount of oil gathering in the pan 12 is to be ignited to vaporize the same before mixing with the air and passing to the burner.

At Figs. 3 and 4 of the drawings I have 95 shown a slight modification of the invention and in which the vaporizing-tube 8' is arranged in a vertical position instead of horizontal, as in the lamp above described, and in the said views the numeral 7' represents the connection for the supply-pipe 2. 6' is the valve for closing the supply of oil to the lamp, and 9' is the peculiar construction of a joint to connect the vaporizing-tube 8', the

same being fitted with the nipple 11' and in line with the bell-mouthed tube 13'. Arranged within this tube 13' is the stem 14', terminating in the conical head 15', which may be adjusted toward or away from the nipple 11', as described. The globe-holder 18' is in this form of a lamp attached to an integral portion 20 of the tube 16' by means of a nut 21 and the burner 17', and the several parts of the lamp are similar to those described while referring to Figs. 1 and 2 of the drawings.

It will be seen by reference to the drawings showing the two forms of a gasolene-lamp embodying the invention that other slight modifications and changes may be made in the general details of construction without departing from the spirit of the invention.

Having thus described my invention, what I claim as new, and desire to secure by Letters Patent, is—

In a lamp of the type described, a mixing-tube carrying a burner, a coupling to which the tube is swingingly connected, a supply-pipe connected to the coupling, a valve-casing connected to the coupling, a cut-off valve arranged in said casing, a vaporizing-tube connected to the valve-casing, a distributor mounted in the coupling with its head in close proximity to the discharge end of the vaporizing-tube, and a starting-pan carried by the coupling and provided with an integral socket to receive the discharge end of the vaporizing-tube, substantially as described.

In testimony whereof I have hereunto affixed my signature in the presence of two subscribing witnesses.

GEORGE RUPPEL.
